UNITED STATES PATENT OFFICE.

EDWARD A. RUDIGIER, OF BALTIMORE, MARYLAND, ASSIGNOR TO STANDARD DEVELOPMENT COMPANY, A CORPORATION OF DELAWARE.

TRANSPORTABLE TANK.

Application filed November 16, 1923. Serial No. 675,077.

To all whom it may concern:

Be it known that I, EDWARD A. RUDIGIER, a citizen of the United States, residing at Baltimore, in the State of Maryland, have 5 invented new and useful Improvements in Transportable Tanks, of which the following is a specification.

This invention relates to transportable tanks and more particularly tanks for carrying materials which are ordinarily difficult to unload in liquid state by reason of their high melting point. The invention will be understood from the following description, taken in connection with the accompanying drawing, in which—

Fig. 1 is a longitudinal vertical section of a tank-car showing an embodiment of the invention;

Fig. 2 is an end view, on larger scale; 20 and

Fig. 3 is a section on the line III of Fig. 1, looking in the direction of the arrows, the scale being that of Fig. 2.

A tank 1 is mounted on any desired means 25 of transport, for example railway-trucks 2 and frame 3, and is provided with a top manhole or inlet 4 and a bottom outlet 5 preferably located at the center. The outlet 5 is guarded by any suitable valve or 30 closure, the detail of which is not material to the present invention, and preferably is elongated transversely of the tank and affords generally a larger opening than customary with tanks for petroleum distillates. 35 Surrounding the tank, or at least about its greater portion, is a spaced wall 6 forming a jacket for a heating fluid, as steam, inlet connection 7 allowing supply of such fluid and connections 8 being provided at the 40 bottom for outlet and drainage. A covering of heat-insulation 9 surrounds the jacket and tank ordinarily, but may be omitted where desired. Traversing the tank from end to end are guides 10 upon which are 45 slidably mounted a pair of pistons 11 one piston for travel in each half of the tank.

In the case of relatively short tanks a single piston will suffice however. Stuffing-boxes 12 are provided on the pistons for 50 making adequately tight packing joints on the guides. At each end of the tank back of the piston is a connection 13 for supply of compressed air or other fluid for propelling the pistons to the center of the tank, 55 and cross supports 14 may be arranged for

the guides and to act also as center-stops for the pistons. By making the guides 10 tubular, (or at least hollow in cases where they are not of circular cross-section) and joining the ends to the inlet and outlet connections 15, 16, steam or other heating fluid may also be thus supplied therethrough so as to heat the interior of the tank. 60

In use, material to be shipped, as for example an oxidized asphalt, is run into the 65 tank while molten, the pistons 11 being back in the ends of the tank as shown in Fig. 1. After arrival at the unloading trestle over a receiving tank at the destination, a steam line is attached to the connection 15, and the 70 outlet 16 and the drains 8 being properly opened or connected to drain lines, steam is supplied to the tank jacket and to the hollow guides 10 until the asphalt softens sufficiently. With the outlet 5 open, a fluid under 75 pressure, preferably compressed air, is supplied by suitable hose or lines attached to the connections 13, and the pistons 11 are forced along toward the center thus discharging the softened load through outlet 5. 80 In this manner highly oxidized asphalts and stiff pitches can be handled as feasibly in tank-cars as materials of low melting point, or such other materials may be handled in weather otherwise prohibitive. After dis- 85 charge of the load the pistons are returned to the ends of the tank, for instance by a fluid under pressure admitted through a central connection 17 the outlet 5 being closed and pressure behind the pistons being 90 released through connections 13, and the tank is ready for another load.

While I have described my invention by reference to certain specific details, it will be understood that this is illustrative and 95 not limitative, and changes may be made which come within the spirit and scope of the invention.

I claim:

1. A car-tank having a central top man- 100 hole inlet and a central bottom outlet, a spaced wall around said tank to form a heating jacket, inlet and outlet connections in said jacket for passage of a heating fluid, a covering of heat-insulation surround- 105 ing said jacket and tank, a plurality of tu- bular guides traversing said tank from end to end, inlet and outlet means for the circu- lation of a heating fluid through said guides, 110 a pair of pistons fitting the interior of the

tank mounted to slide on said guides and having stuffing-boxes thereon, a connection at each end of the tank back of each piston for supply of a propelling fluid, and supports for the guides midway of the tank arranged to act also as center stops for the pistons.

2. A transportable tank having a central top manhole inlet and a central bottom outlet, heating means about said tank, a covering of heat insulation surrounding said heating means and tank, a plurality of tubular guides traversing said tank from end to end, inlet and outlet means for the circulation of a heating fluid through said guides, a pair of pistons fitting the interior of the tank mounted to slide on said guides and having stuffing-boxes thereon, a connection at each end of the tank back of each piston for supply of a propelling fluid, and supports for the guides midway of the tank arranged to act also as center-stops for the pistons.

3. A transportable tank having a top in-

let and a bottom outlet, heating means 25 about said tank, a covering of heat insulation about said heating means and tank, a plurality of guides traversing said tank from end to end, inlet and outlet means for the circulation of a heating fluid through 30 said guides, a pair of pistons fitting the interior of the tank mounted to slide on said guides and having stuffing-boxes thereon, and means for actuating said pistons.

4. A transportable tank having a top inlet 35 and bottom outlet, heating means about said tank, a plurality of hollow guides traversing said tank, inlet and outlet means for the circulation of a heating fluid through said guides, a piston fitting the interior of the 40 tank mounted to slide on said guides, and means for actuating said piston.

5. A transportable tank having guide members traversing said tank, a piston within the tank mounted to slide on said members, and means for actuating said piston. 45

EDWARD A. RUDIGIER.
